UNITED STATES PATENT OFFICE.

CHARLES C. ALLEN, OF KANSAS CITY, MISSOURI.

NECKTIE-SHIELD FOR COLLARS.

No. 885,129.

Specification of Letters Patent. Patented April 21, 1908.

Application filed August 30, 1907. Serial No. 390,800.

To all whom it may concern:

Be it known that I, CHARLES C. ALLEN, a citizen of the United States of America, residing at Kansas City, in the county of Jackson and State of Missouri, have invented a certain new and Improved Necktie-Shield for Collars; and I do hereby declare that the following is a full, clear, and exact description of the invention, such as will enable others to make and use the same, reference being had to the accompanying drawing, forming a part of this specification.

In order to "tie" a neck tie so as to form the bow and particularly the description of necktie known as the "four in hand" worn with the turn down collar, which tie requires more or less lengthening and shortening of the portions of the tie extending from the collar when the collar is buttoned to the shirt band, the application of force to draw the neck tie past the curvature of the collar at the neck is resisted by the collar and the collar is necessarily unbuttoned and removed from the neck band of the shirt in order to locate the tie in its proper position, which is inconvenient and occasions much loss of time. Besides abrading or rumpling of the neck tie results from the force applied to draw the tie between the band and the folds of the collar:

In order to facilitate the tying of the neck tie and at the same time prevent dropping of the tie below the fold of the collar, is the object of the invention, and the manner of performance of which is shown in the accompanying drawing, in which

Figure 1 is a view in perspective of a turned down collar showing the necktie in position and the invention applied to the collar. Fig. 40 2 is a vertical sectional view of the collar and the invention taken upon the line x, x on Fig. 1. Figs. 3 and 4 are enlarged front and rear views, respectively, in detail of the invention. Fig. 5 is a vertical sectional view taken on the line y, y on Fig. 4 and Fig. 6 is a modification of the invention.

Similar numerals of reference indicate corresponding parts in all the figures of the drawing.

50 Referring to the drawing: 10 indicates a turned down collar comprising an inner neck band 11 and an outer fold 12.

13 indicates the hole for the collar button intermediate the ends of the collar, showing 55 the collar button 13^x.

14 indicates a well known neck tie of con-

siderable length and adapted to be tied at the ends into a bow.

15 indicates a thin longitudinal strip of suitable material, preferably made from celluloid, the outer surface being smooth and non-frictional, and the strip forming a non-frictional shield to a portion of the outer surface of the band 11 of the collar. The strip or shield 15 is made of considerable length, a portion 16 of the lower longitudinal portion being stamped out at a point a short distance upwardly and extended outwardly nearly in the arc of a circle so as to form a projection, 16^x, and from said projection the remaining portion of the strip is bent in a curved line and extended upwardly and bent inwardly in grasping contact with the strip 15. The ends of the strip are curved slightly at the corners and inwardly as at 17.

At a point midway the ends of the strip 15 in the portion 16, and the body of the strip 15 is a notch 18, narrow in width, the upper end of the notch being curved in the arc of a circle. Upon the reverse side of strip 15, to the upwardly extended portion 16, is a bead 19, this bead being formed by bending the said upper portion downwardly and inwardly in the arc of a circle, thus forming between the outward bend 16^x and the bead 19 a channel for retaining the necktie.

Upon the inner surface of the body of the strip 15, is a reinforcing piece, 20, secured fixedly to the strip and curved in the arc of a circle. In the reinforcing strip 20 is a notch of the same size and registering with the notch 18 in the strip or shield 15. In the application of the strip or shield 15, to the collar, the body portion is inserted between the band 11 and the fold 12, and being previously flexed, adapts itself to the curve in the collar, the upwardly bent portion 16 extending upon the inner surface of the band 11, and clamping said neck band. The necktie 14, is then placed on the outer surface of the strip which is polished, the necktie being supported by the stamped out portion 16.

The collar is then buttoned to the shirt band in the usual manner and upon applying slight drawing power to the ends of the necktie the tie moves freely over the smooth non-frictional outer surface of the shield so that the bow can be made in the usual manner. In fastening the collar to the neck band, the collar button passes through the notch 18 in the shield and the shield is retained thereby from movement while the necktie is being

arranged in position and moved reciprocally over the surface of the shield. One purpose of the bead 19 on the shield is to prevent the fold 12 of the collar grasping the necktie too closely when the collar is secured to the shirt band and thus affording more space for the movement of the neck tie, the lower outwardly curved portion 16^X of the bend in the strip 15 serving to hold the neck tie from dropping below the neck band of the collar—a channel being formed between these projections 16^X and 19, upon the polished surface of the strip within which the tie is placed.

The shield may be made from metal or 15 hard rubber, if preferred.

I am not aware that a non-compressible bead upon the upper longitudinal portion and the polished surface of the shield has been made prior to my invention, the office 20 of which is to keep the collar away from the

neck tie and thus effecting the main object of the invention, that of preventing the collar from interfering with the free movement of the neck-tie.

Such other modifications may be employed as are within the scope of the invention. 25

Having fully described my invention, what I now claim as new and desire to secure by Letters Patent is:

A necktie shield for turned down collars comprising a longitudinal flexible strip having a polished outer surface and a longitudinally extended bead upon said surface and the upper portion of said strip. 30
